METHOD AND APPARATUS FOR PREPARING AND BINDING BOOKS

Anthony J. Allegretti and Raymond P. Fischer, Chicago, Ill., assignors to The Cuneo Press, Inc., Chicago, Ill., a corporation of Illinois

Application October 14, 1957, Serial No. 689,895

3 Claims. (Cl. 11—1)

This invention relates to method of binding and covering books and the like, and has for one object to make it possible to increase the versatility of printing press equipment by printing two up and binding sidewire or patent bound books one-half size, wherein two pages are printed simultaneously side by side on the same sheet and wherein subsequently, either before or after separation, the pages are cut apart and separately bound.

Ordinarily, when a signature is assembled and a plurality of signatures are brought together in a gathering machine, the signatures are bound together by sidewire binding or patent binding and the book is thereafter trimmed. Under ordinary circumstances, the binding, whether it be sidewire or patent, is placed along the left hand side of the book as you look down on it, and the book then goes on through the processes for final delivery. Under these circumstances, the binding of the signatures into a book takes place along one side, and when the book is trimmed, it is ready for distribution.

This invention involves first printing on each sheet of the signature two book pages where the lines of type are parallel instead of perpendicular to the fold line. Then the book or assembly of signatures will be stitched, preferably by sidewire stitching, as they lie flat, the stitch being at the fold, but each sheet has on it two pages of the book instead of one. The purpose of stitching at the signature is to hold the book together for further manipulation. Once this has been done, the book will be rotated through an angle of ninety degrees with the stitching at the head or at the foot of the page as the case may be. Then the book is cut apart between the pages, the sidewire binding being still left at the foot or at the head of the two pages. Then one book will be fed forward, the remaining book will come down into line with the first one, and then the successive books will be fed through the stitcher and into the covering machine. Before the books reach the covering machine, they will be trimmed, preferably on the three sides but, in any event, on the side along which the first stitching was applied. Thus, the original stitching is really a phantom or disposable stitch, being there for the sole purpose of holding the book together until it can be severed, stitched in the proper place, and covered.

The sequence of covering and severing the two books may be varied. The books might be cut apart and then stitched and then covered, or they might be stitched and covered before they are cut apart. The essential point is that, after the book has been assembled by the proper stitching before or after covering, the two books will be severed. If desired, the head and foot may be reversed in the two books. In that case, the covers might be applied simultaneously, and then after the cover has been applied, one book would have the first page up and the other book would have the last page up. The cover can be severed or cut apart just as the books are, as part of the trimming operation.

It is convenient to hold the signatures together to form a book by stitching. This might be sidewire stitching, or

2

saddle stitching or clamps or pins might be used. An advantage of doing it by stitching is that, since the book must be trimmed any way, trimming discards the phantom binding or holding means, the only loss being a possible slight increase in the amount of paper removed and the necessity of two successive stitching operations.

The invention is illustrated more or less diagrammatically in the accompanying drawings, wherein I have shown three possible variations, all having the same general characteristic, namely: that the book is originally bound or stitched or held along one side, the head or foot side of the printing, is then manipulated so that two sides of the signatures or book will be bound. The two sides will be separately covered and before or after such binding and covering, the two books will be cut apart and the original stitching discarded.

Figure 1 is a flow sheet illustrating one solution of the problem;

Figure 2 is a flow sheet illustrating a somewhat different solution;

Figure 3 is a flow sheet disclosing a modification of the method of Figure 2;

Figure 4 is a detail section through a part of the covering machine.

Like parts are indicated by like characters throughout the specification and drawings.

Referring first to Figure 1, station A is a plan view of the printed material as it will appear in the gathering machine stand, it being understood that this printed material includes a plurality of signatures, arranged one on top of the other, the signatures being separately folded along the line 1, this being the usual fold of the signature. In this case, the fold is along the foot of the book. This assembled book is then fed into the machine trough at station B, being stitched along the line 2, adjacent the fold and lying flat. 3 indicates the drive chain and 4 the pin which propels the book along the trough. At station C, the book contacts a fulcrum pin 5, and is rotated through an angle of ninety degrees into the position shown at station D. There, the two books may be cut apart along the line 6. We have now separated the books into books A and books B, both books being identically arranged. Book B will then be carried forward in station E. Book A will be pushed down into line with the carrying chain and will follow book B in station E, then as each successive book passes along the trough, each one is separately stitched as at 7. The books go on into the covering machine, are covered in the usual manner and, at station F, are trimmed, the trim cutting off the stitching 2 and the edges, shown in dotted lines, and leaving the stitching 7 along the broader edge of the book, namely: the left-hand side as you open the pages.

Referring now to Figure 2, station A is the same as in Figure 1 except that, in this case, the two books are inverted head to foot as indicated, folded in exactly the same way. They then go down into the trough of the machine at station B, are stitched along line 2—2, contact the fulcrum pin or stop 5, to be flipped around through an angle of ninety degrees, to enter station D', but here—

unlike Figure 1, the books are not cut apart. One book is stitched as at 8 and so, now, both books are stitched along one side, the head and foot, and one book is stitched along one side. Then, in station D'', the two books are rotated through one hundred eighty degrees, and the top book is stitched at 8. The book then enters station F, being held by the clamp 10, is presented to the gluing roll at 11, and covered in the usual way. The book is then released, enters station G, is rotated one hundred eighty degrees into the carrier clamp of the second carrying machine, which works just as in station F to cover the opposite book. The book then enters station H,

where the two books are cut apart as at 6 and the three sides are trimmed or, if desired, the head and foot are first trimmed and then cut apart for the finish operation.

The turning or flipping of the book can be accomplished by any of the suitable available book handling mechanisms now in common use and not here illustrated in detail. In Figures 1 and 2, I have illustrated a situation where the book, as it goes through the stitching, covering and gluing method, is generally vertical.

Figures 3 and 4 show a modified arrangement of the method of Figure 2. In this case, the book, having left station D', enters station I, being stitched at 8 and 2 as before. Here, the book is horizontal. It passes between hold-down rollers 110 and is presented to edge-wise glue applicator rollers 12, and then is covered in the covering machine. In this case, the book 13 at station J is provided with a one-piece cover 14—in the previous exemplification, there were two covers, one for each side. This cover will be wrapped around the book by any suitable means, which forms no part of the invention, and the book and cover will then be cut apart along the line 15.

In Figure 4, the book 13 is presented to the vertical rollers 12 with the cover hold-down rollers 11 holding the book against the glue roller. The glue pump 16 will discharge glue through the duct 17 and nozzles 18, against the roller, the doctor blade 19 will insure a proper level of glue, and the remaining glue will be returned to the pump.

It is important that where in the past it has been customary to print a plurality of pages in the signature where the fold line was perpendicular to the line of type in the column, in this invention we propose to increase the capacity or the availability of the press by first printing the pages or columns with the lines of type parallel to the fold line. Then we stitch the phantom or expendable stitches or binding along the fold line merely for the purpose of holding the assembly together so that we can thereafter rotate the assembly through an angle of ninety degrees in the plane of the sheet, after which the pages are bound together by binding perpendicular to the lines of type, that is—perpendicular to the phantom binding

after which either as before or in addition to the trimming action, the phantom or expendable binding is cut away and the separate books may be separated before or after the binding perpendicular to the line of type is applied.

5 We claim:

1. The method of binding books which includes assembling a stack of signatures, each having a plurality of parallel printed pages arranged side by side, head to head and foot to foot, binding the signatures together on a side parallel to the printed lines by disposable stitching, rotating the signatures through an angle of ninety degrees, cutting the signatures apart between adjacent pages to form separate books, aligning the separated books each held together by the disposable stitching, one book behind the other, then binding each book along an edge perpendicular to the printed lines, and then trimming to remove the disposable stitching.

2. The method of binding books which includes assembling a stack of signatures, each having a plurality of parallel printed book pages arranged side by side, head to foot and foot to head, binding the signatures together on a side parallel to the printed lines by disposable stitching, rotating the signatures through an angle of ninety degrees, binding the signatures along opposite edges, perpendicular to the printed lines, cutting the signatures apart between the pages to form separate books and then trimming to remove the disposable stitching.

3. The method of binding books which includes assembling a stack of signatures, each having a plurality of printed book pages arranged side by side, binding the signatures together along one side parallel to the printed lines by a disposable stitching, rotating the signatures through an angle of ninety degrees, binding the pages together along lines, associated with each of the book 30 pages, perpendicular to the disposable stitching, trimming the book and discarding the disposable stitching.
